UNITED STATES PATENT OFFICE.

ARTHUR P. PAINE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

HANGER FOR AXMINSTER-LOOM TUBE FRAMES.

Application filed December 3, 1926. Serial No. 152,480.

This invention relates to improvements in tube frames for Axminster looms and it is the principal object of the invention to provide a rigid suspension member for the chain 5 so constructed as to be readily removable without disturbing the bracket or spool bearing.

Axminster looms employ a pair of spaced endless chains between which extend the 10 tube frames upon which are mounted the yarn spools. Each tube frame is provided at the ends thereof with spool supporting and chain engaging brackets, each bracket having a bearing for a spool gudgeon and 15 also having a tongue to enter the space between a double link of the chain. The chains are trained over guide sprockets and the tube frames pass from one side to the other of a vertical line passing through the centers of 20 the sprockets. This movement of the tube frame subjects the brackets to constant strain and in order to keep the brackets tight 25 they are fixed securely to the tube frames.

When rigid chain engaging latches such 30 as shown in patent to Ryon #1,462,560 are used it is found that renewal of latches can be accomplished only by removing the bracket from the tube frame. After the brackets have been renewed several times they lack 35 the tight fit which they should have to withstand the aforesaid strains. It is accordingly an important object of my present invention to provide a rigid latch which shall be readily removable and renewable without 40 disturbing the setting of the brackets relatively to the tube frame.

It is a more particular object of my invention to provide a spring located inside 45 the hollow bar of the tube frame and removable through aligned openings in the bracket arms and adjacent wall of the tube frame.

With these and other objects which will appear as the description proceeds, my invention relates to the arrangements and combinations of parts hereinafter set forth, and 50 more particularly pointed out in the claims.

In the accompanying drawings, wherein 55 a convenient embodiment of my invention is shown—

Fig. 1 is a vertical central section through 50 a portion of the tube frame having my invention applied thereto, the spool chain and releasing clutch being shown in section and

a portion of the yarn spool being indicated in elevation,

55

Fig. 2 is an end elevation of the structure shown in Fig. 1 looking in the direction of arrow 2 of said Fig. 1,

60

Fig. 3 is a horizontal section taken on the line 3—3 of Fig. 1,

65

Fig. 4 is a view similar to Fig. 1 showing the manner in which the rigid latch and the spring therefor are removed,

65

Fig. 5 is a detail top plan of the horizontally extending arm of the rigid latch looking in the direction of arrow 5 in Fig. 4, and

70

Fig. 6 is a detail vertical section on line 6—6 of Fig. 5.

75

Referring to the drawings it will be seen that I have provided a tube frame 10 having a hollow tubular bar 11 to which are secured a plurality of yarn tubes 12. Each end of the tube frame is provided with a bracket, one of which is indicated in Fig. 1 having a spool bearing member 13 provided with a horizontal leg 14 extending into the hollow tubular bar 11. Said bracket is also provided with a chain engaging member 15 having a horizontal leg 16 extending into the bar 11 along the bottom thereof. Screws 17 may be provided to secure the arms in place and said members may be secured together by having adjacent parts welded to each other. Member 15 has a horizontal slot 18 and an off-set tongue 19 arranged to pass between the links 20 of the transporting chain. A spool is mounted for rotation on the member 13 and has wound thereon a plurality of threads which extend through the yarn tubes 12.

80

The lower end of member 15 may have a projecting lug 21 positioned to lie under the disengaging stud 22 of clutch C, the purpose of the lug being to engage the stud 22 and prevent downward movement of the clutch 95 to effect stopping of the loom as set forth in patent to Striemer #1,546,685. The matter thus far described is old and forms no part of my present invention except the size 100 of the screws 17.

95

In carrying my improvements into effect I provide the lower end of member 15 with a vertical slot 30. Extending between and secured to the vertical walls of the tube frame member 11 is a pin 31 located above 105 the lower leg 16 of the bracket. The rigid

hook member 32 has a head 33 to engage one of the chain elements 20 and said member extends downwardly through horizontal slot 18 and is formed at its lower end with a horizontal extension 34 which passes through vertical slot 30. Said extension 34 is bent to have an upwardly opening notch 35 in the bottom of which is located the pin 31. The inner end of the extension 34 has struck therefrom a tongue 36 which guides the upper end of compression spring 37 and the lower end of said spring is guided by a conical point 38 formed on screw 39. The space between the extension 34 and leg 16 is equal to or slightly greater than the distance between the bottom of the pin 31 and the top of that portion of extension 34 which projects inwardly from the pin.

Under normal operating conditions spring 37 will tend to hold hook member 32 outwardly in the position shown in Fig. 1 with the head 33 lying over one of the chain elements to support the tube frame. At the time of transfer when the tube frame is to be conveyed from the chain to the fabric, stud 22 of the clutch will engage the vertical portion of the hook member and move the same so that head 33 will be out of vertical alignment with the adjacent chain element and the walls 40 of the clutch will be in engagement with the vertical sides of the member 15. After the tufts have been incorporated into the fabric the clutch C will be raised and then moved longitudinally away from the tube frame to permit the head 33 to move over a portion of the chain.

Because of the frequent movement of the hook members they occasionally become bent or broken or for other reasons need replacing. When this condition arises screw 39 may be withdrawn from the tube frame and the spring 37 moved downwardly through the bore for the screw 39. To facilitate this operation the diameter of the spring 37 is preferably slightly less than the bore of the hole which receives the screw 39. With the spring 37 removed the hook member 32 can be moved downwardly so that the upper portion of the extension 34 may pass under the pin 31. Fig. 4 indicates the manner in which the hook may be removed. The new hook can be replaced by an operation the reverse of that described for removing the old hook. In this way the bracket can be held securely in place on the tube frame while the portion most subject to wear is removed and replaced without disturbing the spool.

From the foregoing it will be seen that I have provided a tube frame with a bracket which may be readily renewed without disturbing the setting of the bracket relatively to the tube frame. I do not claim the rigid latch per se as such a device is shown in British patent to Tomkinson et al. #21,644

of 1906, and I do not claim the idea of the latch being connected to the bracket in substantial alignment with the axis of the yarn tubular bearing member, as this construction is old, as may be seen in patent to Greenhalgh #264,281, but I believe I am the first to provide a rigid chain engaging hook member having an extension inside a hollow tubular bar and having contact with the frame in such a way as to permit ready renewal of a damaged hook member without disturbing or in any way interfering with the spool bearing bracket.

Having thus described my invention it will be apparent that changes and modifications may be made therein by those skilled in the art without departing from the spirit and scope of the invention, and I do not wish to be limited to the details herein disclosed but what I claim is:

1. In a tube frame for Axminster looms, a tubular bar, a spool bearing bracket secured thereto, and a rigid hook member pivotally mounted on the bar and readily removable from the tube frame while the bracket is secured to the bar and a spring for said hook member adapted to be inserted through an opening in a side wall of said bar and engaging said hook member when thus inserted and effective to tension said hook member and to prevent accidental displacement thereof.

2. In a tube frame for Axminster looms, a tubular bar, a spool bearing bracket secured thereto, and a rigid hook member extending into the bar and pivotally mounted on the bar and readily removable from the tube frame while the bracket is secured to the bar.

3. In a tube frame for Axminster looms, a tubular bar, a spool bearing member secured thereto, a rigid hook member pivotally mounted with respect to the tubular bar and extending through a portion of the bracket, and connections between the hook member and bar, whereby said hook member may be readily removable while the bracket remains attached to the tubular bar.

4. In a tube frame for Axminster looms, a tubular bar, a spool bearing and chain engaging bracket secured thereto, a rigid hook member having pivotal connection with the tubular bar and extending through a portion of the bracket and being readily removable while the bracket is secured to the tubular member, and resilient means tending normally to hold the hook member in outward position.

5. In a tube frame for Axminster looms having transporting chains, a tubular member, a spool bearing and chain engaging bracket secured thereto, said bracket having an opening therethrough, a rigid hook member pivotally mounted on the tubular member and extending through said bracket

opening, a resilient member engaging that portion of the hook member located within the tubular member, and readily removable means for holding the resilient member in position to cause the same normally to move the hook member outwardly.

6. In a tube frame for Axminster looms having transporting chains, a tubular bar, a spool bearing and chain engaging bracket secured thereto, said bracket having an opening therethrough, a rigid chain engaging hook extending through said bracket opening and into the tubular bar, means defining a pivotal connection between the hook and tube frame independent of the bracket, and resilient means tending to hold the hook outwardly, the pivotal connection between the hook and tubular bar being spaced vertically over adjacent parts whereby the hook may be readily removed while the bracket is secured to the tubular bar.

7. In a tube frame for Axminster looms having a transporting chain, a tubular bar, a spool supporting and chain engaging bracket secured thereto and having an opening therein, a rigid hook member extending through the opening and into the tubular bar, means extending across the interior of the tubular bar to engage the hook and define therewith a pivotal connection for said hook, said means being spaced verti-

cally from adjacent portions of the bracket, whereby the hook may be removed while the bracket is in fixed position relatively to the tubular bar.

8. In a tube frame for Axminster looms having a transporting chain, a hollow member, a spool bearing and chain engaging bracket having spaced parallel arms extending into and secured to the hollow member, said bracket having an opening therethrough, a rigid hook member having a portion lying outside the tubular member and having a portion extending through said bracket opening into the hollow member, said hook member having an upwardly opening notch, a device secured to the hollow member and normally located in the bottom of the notch to afford a pivotal connection between the member and the hook, and resilient means tending to hold the hook against the device and in outward position relatively to the bracket, the depth of the notch being such that the hook can be removed by a combined downward and lengthwise motion relatively to the tubular bar without removing the bracket from the member.

In testimony whereof I have hereunto affixed my signature.

ARTHUR P. PAIN.
